(57) **CLAIM**

The ornamental design for a mesh desk organizer, as shown and described.

DESCRIPTION

FIG. 1 is a perspective view of a mesh desk organizer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of our new design with the drawers extended; and,

FIG. 8 is an enlarged, fragmentary view of the mesh embodied in our new design.

The broken lines in the drawings represent environmental subject matter and form no part of our claimed design.

The jagged lines in the drawings, indicating that no particular handle shape is being claimed, represent boundaries of the claimed design and form no part of the claimed design.
